UNITED STATES PATENT OFFICE.

WILLIAM E. LÉONARD, OF SILVER CREEK, WASHINGTON, ASSIGNOR OF ONE-HALF TO BAILEY WADDINGTON, OF GLENDIVE, MONTANA.

GAS-GENERATING APPARATUS.

No. 851,360.

Specification of Letters Patent.

Patented April 23, 1907.

Application filed May 16, 1906. Serial No. 317,086.

To all whom it may concern:

Be it known that I, WILLIAM E. LEONARD, of Silver Creek, county of Lewis, and State of Washington, have invented a new and 5 useful Improvement in Gas-Generating Apparatus, of which the following is a specification.

My invention relates to gas generating apparatus, and has reference more particularly 10 to the means for the generation of the illuminating or heating gas from wood and analogous vegetable substances.

The invention consists of an apparatus of improved form and construction adapted to 15 extract from the wood, the greatest amount of gas and to leave the by-products, such as charcoal, creosote, carbolic acid, wood-alcohol, etc., in the most favorable condition to be recovered and subsequently utilized.

20 In the accompanying drawings:—Figure 1 is a front elevation of my improved apparatus complete. Fig. 2 is a longitudinal sectional elevation through the furnace and retort on the line *a—a* of Fig. 1, showing the condenser in cross-section. Fig. 3 is a section 25 on the line *b—b* of Fig. 2, the section extending transversely through the retort, longitudinally through the condenser, and centrally through the purifier. Fig. 4 is a 30 transverse section through the retort and furnace on the line *c—c* of Fig. 2, showing particularly the lining for the underside of the retort and the manner of supporting the same. Fig. 5 is a horizontal section through 35 the purifier on the line *d—d* of Fig. 3. Fig. 6 is a perspective view of one end of the retort and the lid-confining yoke. Fig. 7 is a perspective view of the protecting shield for the under side of the retort.

40 Referring to the drawings:—my apparatus comprises as its essential features, a retort 1 to receive the gas generating material; a furnace 2 for heating the retort; a condenser 3 into which the gaseous vapors from 45 the retort pass and are condensed and the heavier matters precipitated; and a purifier 4 through which the gas from the condenser passes and is purified and rendered fit for heating, or illuminating purposes.

50 The retort is in the form of a cylindrical vessel, set horizontally in the furnace with its front portion over the fire box, from which the products of combustion pass

around the retort throughout its length, through the heating space surrounding the 55 retort, and issue from the rear end of the furnace through an opening 2^a in the dome. The retort extends at its opposite ends beyond the end walls of the furnace, and is closed by removable lids or caps 1^a. 60

The lids may be secured to the retort mouths in any manner, which, while hermetically sealing the mouths, will permit the lids to be opened, but I prefer to adopt the construction shown in Figs. 1 and 2, where it 65 will be seen that the projecting ends of the retort have fixed to them at opposite sides plates 1^p provided on their ends with longitudinal lugs 1^r, between which the ends of a yoke 1^b are seated and secured by vertical removable fastening pins 1^c extending through 70 the lugs and yoke. The yoke is provided with a threaded opening in which a threaded stem 1^d is screwed and adapted to bear at its inner end against the lid, and provided on 75 its opposite end with a hand wheel for turning it. In its inner face near its edge, the lid is provided with a circular groove to receive the rim of the retort mouth, in which groove a suitable packing 1^s is seated, so that 80 when the screw stem is tightened up against the lid, the mouth of the retort will be effectually sealed against the escape of gases. By removing one or the other of the confining pins, the yoke may be swung to the right or 85 left as desired, the remaining pin serving as a pivotal support for the yoke. In order that when the yoke is swung on its pivot, the lid may be carried with and supported by it, the latter is formed with openings to loosely receive 90 horizontal pins 1^e projecting outward from the face of the lid. The retort is retained in position in the furnace and prevented from moving endwise when the screw 95 1^d is tightened up against the lid, by means of the plates 1^p.

In order that the under side of the retort may be protected from the effects of the severe heat at the point where it extends over the fire box, and where it is exposed to the 100 direct action of the flame, I propose to provide a shield 1^f of suitable material, arranged to cover the lower surface of the retort at its front. The shield is in the form of a shell, curved to conform to the curvature of the 105 retort, and suspended from the same by

means of hangers 1^h, passing over and around the retort and fastened at their lower ends to lugs on the edges of the shell.

The retort is divided into two communicating chambers, a front main one 1^l, and a rear sub-retort 1^k, a vertical partition 1^l being fixed to the inner side of the retort at a distance from its front end about two-thirds the length of the same. The upper end of the partition terminates some distance below the top of the retort so as to form a communicating passage 1^x between the main and sub-retort. This feature of construction I deem of great importance and advantage, in that it enables the heavier residues precipitated in the condenser, to be returned to the sub-retort, and subjected to a second retorting action, as will be presently described.

20 The condenser is cylindrical in form and arranged horizontally near the rear end of the retort and extends transversely thereof. It comprises an elongated cylindrical water jacket or casing 3^c for the circulation of cold water in which is arranged a condensing coil 3^a. The coil consists of a vertical pipe 3^b entering the casing at one end, and a number of horizontal coils 3^d, the lower coil leaving the casing at the opposite end through vertical pipe 3^e.

25 The gaseous vapors from the retort enter the coil through a vertical pipe 3^f communicating with the vertical pipe 3^h of the coil. The pipe 3^f extends within an enlarged neck or collar 1^m rising from the top of the sub-retort adjacent the partition 1^l, an annular space 1° being thus left between the pipe and the surrounding neck, so that the drippings of the heavier precipitated matters from the 30 condenser as they flow back to the sub-retort in the manner presently to be described, will not adhere to the sides of the neck and clog the same.

35 The lower coil 3^a of the condenser is provided with a collecting basin 3^g having an inclined bottom, into which collecting basin the heavier condensed matters settle as they are freed from the gaseous vapors by the condensing action, the free gas passing out of the 40 coil by the vertical pipe 3^e. The contents of the collecting basin may, from time to time, be returned to the sub-retort for further retorting, by means of a downwardly inclined pipe 3^h leading from the bottom of the basin, and communicating with the vertical pipe 3^b, a globe valve 3ⁱ being provided in the inclined pipe for controlling the passage of the 45 condensed substances.

50 I prefer to introduce the cold water from any suitable source into the water jacket at one end near its base by pipe 3^x and discharge the same from the top of the casing by pipe 3^y.

55 The gas leaving the condensing chamber through pipe 3^e, enters a catch basin 4^a in the

base of the purifier 4, which basin receives the solid matters brought over with the gas from the condenser, and which may be drawn off through cock 4^b. At its center the basin communicates through a vertical neck 4^c with a depending neck 4^d on the bottom of a vertical cylindrical vessel 4^e containing layers of purifying material, the opening in the base of the vessel being covered by an inverted perforated cup 4^f. This vessel is surrounded by a cylindrical casing 4^g rising from the top of the catch basin, and forming an annular space between the casing and the vessel 4^e, through which space the purified gas flows after passing through the purifying 75 layers; and it leaves the purifier by means of a pipe 4^g entering the side of the casing 4^g and leading to a gas holder (not shown) where the gas is stored for use.

80 The upper end of casing 4^g is closed by a cylindrical cover 4^h extending downwardly into an annular body of water 4ⁱ confined in an annular chamber between the casing 4^g and a surrounding water jacket 4^k, these parts forming a water-seal. The top of the 90 cover is provided with an inwardly opening check valve 4^l, which acts to prevent the suction, due to the cooling of the retort, from drawing the water from the water-seal over into the vessel containing the purifying layers. 95 The cylindrical cover 4^h is held firmly in place by means of hinged latches 4^m carried by the cover and engaging lugs or projections on the jacket 4^k.

100 The operation of the mechanism is as follows: The fire being started in the furnace, and wood placed in the retort, the covers are closed and fastened tightly in place so as to hermetically seal the retorting chamber. As the wood is subjected to the action of the 105 heat, it throws off gas-containing substances in the form of a gaseous vapor, which passes over into the sub-retort where it is superheated and becomes a fixed gas. From the sub-retort the gas enters the condensing 110 chamber where, being subjected to the cooling action of the circulating water, the vapors are condensed, and the heavier tarry matters held in suspension, are precipitated, and settle in the collecting basin 3^g from 115 which they are returned through pipe 3^h to the sub-retort for a further retorting action in order to effectually extract all gaseous matter. From the condenser, the gas, freed of all its heavier substances, passes to the 120 purifier, where it is subjected to a purifying action, and leaving the same it is conducted to a gas holder and stored for use.

125 Having thus described my invention, what I claim is:

In a gas generator, the combination of a retort formed at its front with a main retorting chamber and at its rear with a sub-retorting chamber, which chambers communicate at the top, the main retorting chamber 130

extending for nearly the entire length of the retort proper, and each of said chambers being unobstructed throughout, a condenser communicating with the sub-retorting chamber, and means whereby the accumulated condensate may be discharged at will into the sub-retort.

In testimony whereof I hereunto set my hand this 7 day of May, 1906, in the presence of two attesting witnesses.

WILLIAM E. LEONARD.
